UNITED STATES PATENT OFFICE.

JOSEPH MOSS, OF WOONSOCKET, RHODE ISLAND, ASSIGNOR TO WOONSOCKET MACHINE & PRESS CO., INC., OF WOONSOCKET, RHODE ISLAND, A CORPORATION OF RHODE ISLAND.

CONDENSER CYLINDER FOR FIBER-PREPARED MACHINES.

Application filed October 6, 1923. Serial No. 667,061.

To all whom it may concern:

Be it known that I, JOSEPH Moss, a citizen of the United States, residing at Woonsocket, in the county of Providence, State of Rhode Island, have invented a certain new and useful Improvement in Condenser Cylinders for Fiber-Preparing Machines, of which the following is a specification, reference being had therein to the accompanying drawings.

The invention has relation in general to the condenser cylinders or cages which are used in fiber preparing machines, and more particularly to the means of securing the sheet metal shells of such cylinders or cages in place upon the heads or spiders thereof. The invention is applicable also in the case of other cylinders of the same general structure.

Condenser cylinders or cages, to the construction of which the invention primarily is designed to be applied, commonly are employed as elements of openers, pickers, and other machines employed for operating upon cotton and other fibrous material. In operation, the air within a condenser cylinder or cage is withdrawn through one or both ends of the cylinder or cage, or the side opposite the receiving side thereof, so as to produce a suction through the perforations of the cylinder shell, and fibrous material carried toward the cylinder by an oncoming current of air from the beater of an opener or picker collects on the exterior of the said shell, and is discharged therefrom in the form of a sheet or bat as the cylinder revolves.

Heretofore the perforated sheet material constituting the shell of a condenser cylinder or cage customarily has been secured in place in connection with the supporting heads or spiders through the application of solder. The results incidental to the use of solder have frequently proved unsatisfactory. The heat necessary in melting and applying the solder in the work of constructing the cylinder or cage causes frequently more or less warping and distortion of the sheet metal and resulting departure from the true cylindrical form that is desired. Also, after installation of the cylinder or cage, in the event of fire starting in the opener or picker in connection with which

the condenser cylinder or cage is employed, and being carried by the flaming flying particles of cotton to the cylinder or cage, as almost invariably is the case, the heat melts the solder by which the sheet metal covering or shell is held in place, so that the joints of the latter open or separate. This necessitates removal of the cylinder or cage, repair or substitution entailing considerable expense, and an enforced suspension of the use of the opener or picker.

The object of the present invention is to provide an improved construction of condenser cylinder or cage, or the like, which will do away with the use of solder and enable the shell to be applied and fastened in place so that it will be perfectly secure, without loss of the true cylindrical shape which is desired, and without liability to injury such as aforesaid in case of fire in the opener or picker with which the cylinder or cage is employed. Also, to provide a construction enabling the shell, in whole or in part, to be speedily and inexpensively replaced when necessary, so as to restore the cylinder to perfect condition.

The invention consists in a condenser cylinder or cage, or the like, having a plurality of heads or spiders, with each of the said heads or spiders formed with one or more slots or recesses in its periphery, a cylindrical shell comprising one or more circumferential sections of sheet material fitted to the peripheries of the said heads or spiders and having meeting edges formed with inturned flanges, and clamping members extending lengthwise of the cylinder, fastened together with the said inturned flanges between them, and occupying the said peripheral slots or recesses of the heads or spiders. The invention includes also means for preventing displacement of the shell lengthwise of the cylinder.

An illustrative embodiment of the invention is shown in the accompanying drawings, in which,—

Fig. 1 is an end view of a condenser cylinder or cage containing the features of the invention, showing the means for and manner of clamping together the meeting edges of the sheet material, and securing them within the peripheral slots in the supporting heads or spiders.

Fig. 2 is a side view, partly in section on line 2, 2, of Fig. 1, certain parts being broken away.

Fig. 3 is a view of the various parts 5 which are immediately concerned with the invention, in disassembled relations.

Fig. 4 is a view on a larger scale than the preceding views, in section on line 4, 4, of Fig. 5, looking in the direction indicated 10 by the arrows.

Fig. 5 is a view on the same larger scale, in section on line 5, 5, of Fig. 4, looking in the direction indicated by the arrows.

Having reference to the drawings,—

15 The head or spider 1 at each end of the cylinder, and intermediate spider 15 when the latter is employed, are each formed as heretofore with a flanged circular periphery 2 to receive the perforated material 3 constituting the shell of the cylinder, and with a hub 4 by means of which the cylinder is mounted upon a shaft 5 for revolution, the respective heads or spiders being fixed to said shaft by means of keys 6. The heads 20 or spiders differ however from those of prior constructions in that each thereof is provided with one or more slots or recesses 7, 7, in its periphery. The said perforated material 3 is formed at the meeting edges 25 thereof with flanges 8, 8. As will be apparent, the perforated material may be in one continuous sheet extending completely around the heads 1 and constituting a one-piece shell, or may be made as illustrated herein of a plurality of sheets constituting 30 sections of the shell. The two flanges 8 at the meeting ends of the sheet of perforated material, if one continuous piece is used, or at the meeting edges of two adjacent sheets, 35 as in the construction shown here, are brought together within slots or recesses 7, 7, of the heads or spiders, and clamped between clamping members 9, 9, comprising two longitudinal strips, also occupying the 40 slots 7, 7, and extending the full length of the cylinder. The clamping members 9, 9, and likewise the meeting edges, are drawn together by means of a closely spaced series 45 of bolts 10, 10, occupying holes 11, 11, in the strips or clamping members 9, 9, and also through correspondingly spaced holes 50 12, 12, in the flanges 8, 8, and furnished with nuts 100, 100. To prevent the shell 55 from moving longitudinally on the heads or spiders, a block of metal 13 is secured beneath the head of the bolt 10 at each end of the longitudinal joint formed by the 60 said flanges and clamping members. This block 13 bears against the inward face 14 of the material of the adjacent end head just at the side of the slot or recess 7, as shown in Fig. 5, and effectually prevents any tendency of the shell to slip over the heads lengthwise.

In this construction of condenser cylinder 65 the perforated material 3 can be given a true cylindrical curvature, as in Fig. 3, prior to installation on the heads. When fitted in place upon the heads, it is not subject to any distorting influences and is 70 drawn down securely into a close fit upon the peripheries of the heads or spiders by simply tightening the bolts 10, 10, to draw together the adjoining flanges 8, 8, at each longitudinal joint. In the event of damage 75 to one or all of the sheets of perforated material by fire or other agency, it is evident that such sheet or sheets may be speedily and inexpensively replaced to make the condenser cylinder as good as new. 80

What is claimed as the invention is:—

1. A condenser cylinder for fiber preparing machines having a plurality of heads or spiders, with each of the said heads or spiders formed with one or more slots or 85 recesses in its periphery, a cylindrical shell of sheet material fitted to the peripheries of the said heads or spiders and having its meeting edges formed with inturned flanges, and clamping members extending lengthwise of the cylinder, fastened together with the said inturned flanges between them, and occupying the said peripheral slots or recesses of the heads or spiders. 90

2. A condenser cylinder for fiber preparing machines having a plurality of heads or spiders, with each of the said heads or spiders formed with one or more slots or recesses in its periphery, a cylindrical shell of sheet material fitted to the peripheries of the said heads or spiders and having its meeting edges formed with inturned flanges, clamping members extending lengthwise of the cylinder, fastened together with the said inturned flanges between them, and occupying the said peripheral slots or recesses of the heads or spiders, and means connected with said clamping members engaging with a head or spider to prevent endwise movement of the sheet material. 105

3. A condenser cylinder for fiber preparing machines having a plurality of heads or spiders, with each thereof formed with one or more peripheral slots or recesses, a cylindrical shell of sheet material fitted to 115 the peripheries of the said heads or spiders and having its meeting edges formed with inturned flanges, longitudinal clamping members between which said flanges are interposed, bolts disconnectibly fastening 120 such members together with the flanges between them, the said members and interposed flanges occupying the said peripheral slots or recesses, and blocks bolted to 125 said members and holding the shell from endwise movement relative to the heads or spiders.

JOSEPH MOSS.
